UNITED STATES PATENT OFFICE.

LELAND L. SUMMERS, OF CHICAGO, ILLINOIS.

RETORT.

1,422,634.

Specification of Letters Patent. Patented July 11, 1922.

Application filed August 12, 1920. Serial No. 402,944.

To all whom it may concern:

Be it known that I, LELAND L. SUMMERS, a citizen of the United States, residing at Chicago, in the county of Cook and State of Illinois, have invented certain new and useful Improvements in Retorts, of which the following is a specification.

This invention relates to coke retorts.

One object of the invention is to improve 10 the construction of coke retorts for producing an improved grade of coke.

Another object is to cause the proper feeding 15 of the material and its compression throughout the entire height of the retort and to cause ready and unimpeded movement of such material through the retort.

These and other objects are accomplished 20 by means of the arrangements disclosed on the accompanying sheets of drawings, in

20 which—

Figure 1 is a fragmentary longitudinal sectional view of a coke retort embodying my invention;

Figure 2 is a transverse sectional view 25 taken in the plane of line 2—2 of Figure 1;

Figure 3 is a sectional view of the same retort taken in the plane of line 3—3 of Figure 1; and,

Figure 4 is a longitudinal sectional view 30 through a modified form of retort embodying my invention.

In my former Patent, No. 943,610 of December 14, 1909, I have shown a coke oven in which the material to be coked is fed from a 35 vertical hopper to a reciprocating, horizontal floor, by means of which floor the material is fed through the oven during the coking process. It will be noted that in this prior patent the floor is considerably wider than the height of the sides of the retort, the heat, as shown in this patent, being preferably applied from the upper wall of the retort.

In this construction the friction between 45 the material and the floor is sufficient to overcome the friction between the material and the side walls of the retort, so that the movement of the floor toward the discharge end of the oven carries the material toward the 50 discharge end, while the opposite movement of the floor results in a high compression of the material in the retort.

In the present application, I show a retort in which the heating ducts are in the 55 side walls of the retort. This necessitates a narrowing of the retort in order that the

heat may pass through the material under treatment to a sufficient degree. The narrowing of the reciprocating floor, however, in such a retort results in a loss of frictional 60 resistance between the material and the floor and an increase in such resistance between the material and the side walls.

In order, therefore, to provide in this type of oven a sufficient frictional resistance 65 between the material and the floor as will enable the floor to feed the material through the oven and at the same time produce the desirable compression, I provide the floor with a fixed fin or die, which in effect forms 70 a part of the floor in the sense that it provides an additional friction surface for the floor. This friction surface extends into the body of the material so as to cause all layers of the material to move with the movement 75 of the floor.

Referring to Figures 1 to 3, it will be noted that I have shown the horizontal type of retort having a horizontally extending walled chamber 10 for the reception of carbonaceous material which is supplied vertically through a bin or chute 11. The coal on passing vertically downward by gravity through the bin 11 is deposited upon the forward end of the reciprocating conveyor 12 80 which is actuated back and forth by a suitable ram mechanism 13. As shown in Figure 1, the conveyor 12 is in its rearwardmost position. Let it be assumed that the chamber 10 is filled with carbonaceous material 85 in various stages of distillation, such, for example, as raw coal in the forward end, carbonaceous material in a plastic state intermediate the length of the retort, and solid coke at the rear end thereof, it being understood, of course, that the walls of the chambers 10 are heated by any suitable heating medium passing through ducts 14, as is usual in retorts of this nature, the distilled gases from the carbonaceous material passing through 90 an outlet 15 to any suitable main 16. With the conveyor 12 in the position shown in the figures of the drawings and with the carbonaceous material in the different stages above described, let it be assumed that the conveyor 12 is drawn outwardly from the oven. Such movement causes a compression of the 95 carbonaceous material in the chamber 10, and particularly of the material which is in a plastic or semi-plastic condition; also at 100 the same time some of the rigidly formed coke at the rear end of the oven is pushed

105

110

off of the conveyor 12 into the coke chute 17. As the conveyor is thrust back into the retort, space is left at the forward end thereof for the reception of an additional supply 5 of raw coal which automatically falls by gravity through the chute 11 to take up the unoccupied space on the conveyor preparatory to another outward movement of said conveyor for progressively feeding the carbonaceous material in different conditions 10 rearwardly toward the coke chute end.

By practice it has been found that where a large uninterrupted mass of heavy material is passed through a retort of the kind 15 described, not always does the heat penetrate through the carbonaceous material for causing proper distillation thereof, and, furthermore, under such conditions there is an added tendency for such material, as it becomes 20 plastic to adhere to the walls, thus increasing the difficulty of moving the material, and also resulting in poor compression, especially in the upper part of the chambers or ovens, which upper parts many times may 25 not be filled.

To overcome all of these disadvantages, I have provided what I choose to call a fin or die 18 which is mounted upon and movable with its associated conveyor 12. In 30 Figures 2 and 3 I have shown two forms which this fin or die may assume. Of course, it is understood that the same may assume other forms, but preferably I have shown at the left hand side of Figure 2 a simple 35 vertical fin 18 which extends vertically from the conveyor 12 to a point directly adjacent the upper wall of the oven or chamber 10, thereby dividing said chamber into two parts whereby the heat from the walls may more 40 readily penetrate through a relatively thin mass of carbonaceous material for distilling same. At the same time, as the floor with its material passes through the retort the material adheres readily to the fin 18. The 45 fin is a size such that the area of the fin and floor in contact with the material is greater than the area of the chamber or retort walls with the material. This, owing to the increased friction due to the fin, results in a 50 compression of the carbonaceous material throughout the entire height of the fin and at the same time renders progressive movement of the carbonaceous material a simpler and easier matter.

At the right hand side of Figure 2 I have 55 shown a modified form of fin 19, the main portion of which extends vertically in the chamber 10 and has laterally extending flanges or shelves 20 forming pockets in 60 which the material is compressed and given the form outlined by the openings between said flanges.

It will be understood, of course, that these 65 pockets on the side of the fin may be formed in any desired configuration, so that as the

plastic portion of the material is forced through these pockets under heavy compression this plastic mass may be thus formed in the desired shape, so that in this way the briquettes of heavily compressed carbonized 70 material may be made during the coking operation and without interruption to the coking.

In Figure 4 of the drawings I have shown my invention in connection with a modified 75 form of retort, the same including a vertical distilling chamber 21 in which preferably low temperature is maintained for driving off the more volatile products, raw coal being passed into the vertical chamber in any 80 suitable manner. Instead of the carbonaceous material being conveyed as raw coal to the horizontal chamber 10, as in Figures 1, 2 and 3 of the drawings, the carbonaceous material in the arrangement shown in Figure 85 4 is passed to the horizontal chamber 10 in a partially distilled condition, and, as a matter of fact, being in a plastic or semi-plastic condition ready for further distillation and compression when it reaches the 90 horizontal chamber. Otherwise the parts are the same as described hereinabove. By means of this arrangement compression may be applied to the carbonaceous material throughout the height of the horizontal 95 chambers or retorts and materials may be handled in a plastic or sticky condition in which they tend to adhere or become attached to side walls or other portions of the retort, the adhesion to the fin causing them 100 to become compressed so that such plastic materials may be readily conveyed through the retort. The fin, being embedded in the carbonaceous material, since it is arranged intermediate the longitudinal edge of the 105 conveyor floor, is not directly exposed to the action of the heat and is, therefore, at all times surrounded by a protecting covering of carbonaceous material. The dimensions of the fin may be such as to occupy 110 any desired portion of the retort space, and accordingly thin layers of carbonaceous material may be conveyed through the retort with a rapid penetration of heat through the relatively thin layers of such material, 115 which, however, is rigidly held by the fin so that the form and structure of the material may be preserved and its physical structure may be held independently of the rapidity with which the heat is applied. The car- 120 bonaceous material may, therefore, be subjected to rapid distillation and yet its physical structure may be maintained in a dense condition.

The fin attached to the reciprocatory con- 125 conveyor extends longitudinally of the conveyor, preferably for approximately the full height of the retort, though it may extend the full height of the retort for only a portion of its length and be of less height for 130

the remaining portion of its length. This fin may extend the entire length of the retort, or only partially the length of the same, these conditions depending somewhat upon 5 the character of the carbonaceous material being treated in the retort. In practice, I prefer to have the fin extend the full height of the retort but only partially through the length of the same, as I have found this to 10 be sufficient to obtain the desired movement and compression upon most kinds of carbonaceous material.

While I have illustrated and described herein one method of increasing the frictional resistance between the floor and the material being conveyed thereby, it is my 15 intention in the following claims to cover all such modifications which do not involve a departure from the spirit and scope of my invention, as I believe that I am the first in 20 this art to suggest any means for feeding material through a retort of less width than height by increasing the frictional resistance between the floor and the material carried 25 thereby.

I claim:

1. A coke oven comprising a retort having relatively large side wall area as considered 30 in relation to the floor area, a reciprocating floor in said retort, means for feeding material to one end of said floor and for restraining the material against movement except in a direction toward the retort, and means for increasing the frictional resistance 35 between the floor and the material.

2. In a coke oven, a retort having heating ducts in its side walls, a reciprocating floor in said retort, said floor being substantially less in area than the side walls of the retort, means 40 for feeding carbonaceous material to one end of said floor and for withdrawing material from the opposite end of the floor, and means fixed to said floor and extending longitudinally thereof for causing frictional resistance 45 between the floor and the material.

3. In a coke oven, a retort having heating ducts in its side walls, a reciprocating floor in said retort, means for feeding carbonaceous material to one end of said floor and 50 for withdrawing material from the opposite end of the floor, and a fin fixed to said floor and extending longitudinally thereof for causing frictional resistance between the floor and the material.

55 4. In a coke oven, a substantially horizontal retort having heating ducts in its side walls, a reciprocating floor in said retort, means for feeding carbonaceous material to one end of said floor and for withdrawing 60 the material from the other end of said floor, means fixed to said floor and extending longitudinally thereof intermediate the longitudinal edges of the floor for causing fric-

tional resistance between the material and the floor.

65

5. In a coke retort, a walled chamber for the reception of carbonaceous material, a conveyor mounted in said chamber for causing a progressive movement of said material, and a fin carried by said conveyor to which 70 the carbonaceous material clings.

6. In a coke retort, a walled chamber for the reception of carbonaceous material, a conveyor mounted in said chamber for causing a progressive movement of said material, 75 and means carried by said conveyor and extending longitudinally thereof and upwardly into the material and to which the carbonaceous material clings.

7. In a coke retort, a walled chamber for 80 the reception of carbonaceous material, a conveyor mounted in said chamber for causing a progressive movement of said material, and a vertically arranged fin carried by said conveyor for causing said material to 85 be compressed throughout the entire height of the chamber when said material is subjected to compression.

8. In a coke retort, a walled chamber for 90 the reception of carbonaceous material, a conveyor mounted in said chamber for causing a progressive movement of said material, and a vertically arranged fin having laterally extending flanges carried by said conveyor.

95

9. In a coke oven, a retort having relatively large side wall area as considered in 100 relation to the floor area, a reciprocating floor in said retort, means for feeding material to one end of said floor and for restraining the material against movement except in a direction toward the retort, and means fixed to said floor and extending into the mass of material on the floor for causing the material to move with the floor.

105

10. In a coke oven, a retort, a reciprocating floor in said retort, means for feeding material to one end of said floor and for restraining the material against movement except in a direction toward the retort, and a fin fixed to said floor and extending into the mass of material on the floor for causing the material to move with the floor.

110

11. In a coke oven, a retort, a reciprocating floor in said retort, means for feeding material to said floor and for restraining the material against movement except in a direction toward the retort, means fixed to said floor for causing the mass of material to move with the floor, said means being 115 provided with die portions for shaping the plastic portion of the material during the movement of the floor.

120

Signed at Chicago, Illinois, this 30th day of July, 1920.

LELAND L. SUMMERS.
